UNITED STATES PATENT OFFICE.

JOHN BORYK, OF ANSONIA, CONNECTICUT.

SAFE-LOCK.

1,337,386.

Specification of Letters Patent. Patented Apr. 20, 1920.

Application filed June 27, 1918. Serial No. 242,193.

To all whom it may concern:

Be it known that I, JOHN BORYK, a citizen of Russia, residing at Ansonia, county of New Haven, and State of Connecticut, 5 have invented certain new and useful Improvements in Safe-Locks, of which the following is a specification.

This invention relates to improvements in locks, particularly to types adapted to be 10 used in connection with safes and other like containers where positive security is required.

The principal object of the invention is to provide means whereby unbolting of the 15 lock mechanism is prevented except by the prior manual retraction of a detent remote from and not readily recognizable as a part of the lock, whereby a double means of security is afforded, this invention being particularly applicable to a novel form of lock 20 for which I have made application for Letters Patent in the United States, Serial No. 238,860 and which describes in detail the lock construction.

25 The purposes of the invention are attained by the novel construction and combination of parts hereinafter described and shown in the accompanying drawings, forming a material part of this disclosure, and 30 in which:—

Figure 1 is a front elevational view showing a conventional type of safe and indicating the application of the invention.

Fig. 2 is a fragmentary front elevational 35 view of the same, the safe door being shown in an open position.

Fig. 3 is a sectional view taken on line 3—3 of Fig. 1; and

Fig. 4 is a sectional view, taken on line 40 4—4 of Fig. 3.

Referring now more specifically to the drawings, the numeral 10 indicates the base of the safe resting upon rollers and casters 11, the entire front of the safe being normally covered by doors 12, secured by hinges 45 in the ordinary manner.

The interior of the safe may be compartmented and an inner door 14 used to protect the more valuable contents contained within 50 the drawers 15. The door 14 is mounted upon hinges 16, and is formed with abutting stepped edges 17, engageable within the corresponding side walls 18 of the safe, which are surrounded with asbestos or outer 55 material adapted to prevent the transmission of heat should a conflagration occur, this

lining being held within an exterior casting 19.

Attached to the inner side of the door 14 is a lock casing 20 in which a plurality 60 of bolts 21 are operably engaged with a horizontal bar 22, normally spring actuated into a retracted position, and which are manipulated by lock mechanism of any suitable character. 65

Contactable with the center locking bolt 23 is a lever 24, pivoted on a pin 25 set in the lock casing, while the outer end of the lever is pivotally engaged with a fork 27, secured on the end of a rod 28 which extends outwardly through the lock casing 20, and is guided by a fixed bracket 29, the extreme end of the rod being so positioned that a collar 30, fixed upon a slidable rod 31 may make contact with it, pressing the 75 bolts into full operative or engaging position and preventing their retraction when in a forward position.

The rod 31 extends through the lock casing 18, and has upon its outer end a fixed 80 collar 32, between which, and a loose collar 33, is positioned an encircling compression spring 35, normally holding the bar 31 in its outermost position. Engaged upon the exterior of the inner casing 18, by hinges 85 32, is a vertical bar 40, having an extending operating handle 41, while affixed upon the vertical bar 40 upon the uppermost inner side is a stem 42, carrying at its outer end a block 43 adapted to pass through the opening 44, formed in the front lock casing, and when the handle 41 is turned outwardly it causes the block 43 to make contact with the extending head 32, pressing the sliding bar 31 forward and, by reason of its contact with the end of the bar 28, holding the lock bolts in their engaged position and preventing their retraction until the handle 41 is turned in the manner indicated. Thus, if the bar 41 be turned outwardly and left 90 40 in that position in which it is engaged and held by the catch 44', the bolts are prevented from being retracted, or if the bolts are partially retracted as shown in Fig. 4 and it is desired to open the door, the bolts 100 must first be pressed outward to their full extent in order for the lock mechanism to be operated.

Having thus described my invention what I claim as new and desire to secure by Letters Patent, is—

1. In a device for preventing the retrac-

tion of bolts, the combination with a lock casing and a bolt slidable therein, of a lever pivoted in said casing, said lever engaging with one of said bolts, a rod pivoted to the 5 extreme end of said lever and extending through said lock casing, a bar hinged vertically at the rear of said lock, a handle on said bar by which it may be operated, and an extending element secured to said bar 10 adapted to make contact with said rod, whereby it is prevented from retraction.

2. In a bolt locking device the combination with a casing, a plurality of bolts operable therein, said bolts being engageable 15 with a fixed keeper, of a lever pivoted in said casing, said lever engaging with one or more of said bolts, a rod pivotally attached to the free end of said lever and extending through said casing to a point remote 20 therefrom, a detent arm contactable with the outer end of said rod by which it is pre-

vented from being operated, and means for actuating said detent arm from the exterior of the door upon which said lock is engaged.

3. In a bolt locking device the combination with a casing, a plurality of bolts operable therein, said bolts being engageable with a fixed keeper, of a lever pivoted in said casing, said lever engaging with one or 25 more of said bolts, a sectional rod, one of the sections being pivoted to said lever, means for guiding said rod, means for normally holding the other section of said rod in an extended position, an arm adapted to make 30 contact with the last named section of said rod, and means for actuating said arm whereby said bolts are held in an engaged position.

In testimony whereof I have affixed my 35 signature.

JOHN BORYK.
